(57) **CLAIM**

The ornamental design for a stackable bulk fluid storage container, as shown and described.

DESCRIPTION

FIG. 1 is an upper perspective view of the stackable bulk fluid storage container;

FIG. 2 is a lower perspective view of the stackable bulk fluid container shown in FIG. 1;

FIG. 3 is a top plan view of the stackable bulk fluid storage container shown in FIG. 1;

FIG. 4 is a bottom plan view of the stackable bulk fluid storage container shown in FIG. 1;

FIG. 5 is a right-side elevation view of the stackable bulk fluid storage container shown in FIG. 1;

FIG. 6 is a left-side elevation view of the stackable bulk fluid storage container shown in FIG. 1;

FIG. 7 is a front elevation view of the stackable bulk fluid storage container shown in FIG. 1; and,

FIG. 8 is a rear elevation view of the stackable bulk fluid storage container shown in FIG. 1.

The broken lines shown in the figures represent portions of the stackable bulk fluid storage container that form no part of the claimed design.

1 Claim, 7 Drawing Sheets
